Primary Examiner — Keli L Hill*Assistant Examiner* — Harold E Blackwell, II(74) *Attorney, Agent, or Firm* — LegalForce RAPC Worldwide(57) **CLAIM**

The ornamental design for a VESA mount adaptor bracket, as shown and described.

DESCRIPTION

FIG. 1 is a front top right side perspective view for a VESA mount adaptor bracket, showing my new design; FIG. 2 is a front elevational view of FIG. 1 thereof; FIG. 3 is a rear elevational view of FIG. 1 thereof; FIG. 4 is a left side elevational view of FIG. 1 thereof; FIG. 5 is a right side elevational view of FIG. 1 thereof; FIG. 6 is a top plan view of FIG. 1 thereof; FIG. 7 is a bottom plan view of FIG. 1 thereof; and, FIG. 8 is an exploded front top right side perspective view of VESA mount adaptor bracket of FIG. 1 thereof. The broken lines indicate unclaimed portions of the design and form no part of the claimed design.

1 Claim, 8 Drawing Sheets(56)
